UNITED STATES PATENT OFFICE.

ALBERT J. HORTON, OF WHITE PLAINS, NEW YORK, ASSIGNOR TO THE CUTLER-HAMMER MFG. CO., OF MILWAUKEE, WISCONSIN, A CORPORATION OF WISCONSIN.

MOTOR-CONTROLLER.

1,268,574.

Specification of Letters Patent.

Patented June 4, 1918.

Application filed June 4, 1915. Serial No. 32,078.

To all whom it may concern:

Be it known that I, ALBERT J. HORTON, a citizen of the United States, residing at White Plains, in the county of Westchester 5 and State of New York, have invented new and useful Improvements in Motor-Controllers, of which the following is a full, clear, concise, and exact description, reference being had to the accompanying drawing, forming 10 a part of this specification.

This invention relates to improvements in motor controllers.

More particularly the invention relates to controllers for motor-driven printing presses 15 but, as will later be apparent, it is not limited to this particular application thereof.

One of the objects of the invention is to provide push button governed control means wherein a single button may be employed 20 for effecting various different functions including starting, acceleration and deceleration.

A further object is to provide push button governed means wherein two push button 25 switches will provide for starting for inching and continuous operation, for speed regulation including acceleration and deceleration and for stopping at will.

Various other objects and advantages of 30 the invention will hereinafter appear.

The accompanying drawings illustrate dia- 35 grammatically two of the numerous possible embodiments of the invention and the same will now be described.

Figure 1 diagrammatically illustrates a controller wherein the speed regulation is effected by one means, and

Fig. 2 diagrammatically illustrates a sim- 40 ilar controller wherein the speed regulation is effected by an alternative means.

Referring to Fig. 1, the controller is illus- 45 trated as governing a compound wound motor 1 having an armature A, a series field F, and a shunt field f. The controller in- cludes an electro-responsive main switch 2, an electromagnetic accelerating device 3, an electro-responsive relay switch 4 functioning with said device, a manual regulating device 5 and a push button control station 6.

The switch 2 is responsive to complete the 50 motor circuit through a set of contacts 2^a and when deenergized completes, through a set of contacts 2^b, a dynamic braking circuit for the motor including a suitable braking 55 resistance r. The switch 2 also has a set of

auxiliary contacts 2^c for a purpose herein- after set forth.

The accelerating device 3 is of a conven- 60 tional form, comprising a plurality of switch arms 7 to 13 to be progressively moved to circuit closing position by an operating sole- 65 lid 15 and an additional switch arm 14 normally standing in circuit closing position and operable from such position following the movement of arm 12 to circuit closing 70 position. The switch arms 7 to 12 control a starting resistance R for the motor and serve to remove said resistance from circuit in steps. The switch arm 13 controls the energizing circuit of the relay switch 4 75 which, upon response, short circuits the starting resistance R. The switch arm 14 functions in conjunction with the speed reg- 80 ularating device 5, and, as will hereinafter ap- 85 pear, serves to short circuit a part of the 90 same.

The regulating device 5 is also of conven- 95 tional form and comprises a pivoted arm coöperating with a series of contacts 20 to control an armature resistance R' for the 100 motor and with a series of contacts 21 to control a resistance R² for the shunt field circuit of the motor. The arm is movable in a clockwise direction to exclude the arma- 105 ture resistance R' from circuit and to there- 85 after insert the field resistance R² in circuit. During movement of the arm over the but- 90 tons 20 said arm bridges segments 22 and 23 to complete the field circuit exclusive of the resistance R² and during movement of the 95 arm over the field resistance contacts 21, said arm engages a segment 24 to complete the armature circuit exclusive of the resist- 100 ance R'. The arm of the speed regulating device is adapted to be set in any desired 105 position according to the ultimate speed de- 110 sired and the above mentioned switch arm 14 of the accelerating device serves in circuit closing position to short circuit all of the field resistance which may be included in circuit by the setting of the regulator arm. Thus as the switch 14 is maintained in circuit closing position until after closure of accelerating switches 7 to 12, it will be ob- 115 served that full field strength of the motor is insured during the starting period.

The push button control station 6 is of the same general type as that illustrated in my prior Patent No. 1,122,931, Dec. 29, 1914, in which the switches are provided with adjust- 110

able stops whereby they may be set in different normal positions with consequent variations in function upon depression and release thereof. More specifically the station 5 includes a switch 25 biased to engage and bridge contacts 26 and restrainable by a pin 25^a and stop 25^b in the dotted line position. Also, the station includes a switch 27 biased to engage and bridge contacts 28 and movable from said biased position to engage and bridge contacts 29. This switch is also provided with a pin 27^a and stop 27^b to limit its upward movement to the dotted line position at the same time leaving the same free to 10 move into and out of engagement with contacts 29.

Briefly set forth, the controller functions as follows:

With certain settings of the push button 20 switches depression and release of the switch 27 effects response and deenergization of main switch 2 for inching. Again, with other settings of the switches depression of switch 27 functions to energize main switch 25 2 for starting the motor for continued operation at slow speed and subject to stopping by depression of switch 25. Again, with the switches set in the position illustrated, full depression of switch 27 effects energization 30 of the switch 2 for starting while its return to normal position energizes solenoid 15 of the device 3 for accelerating the motor to a speed determined by the setting of the regulating device 5. Upon full operation of the 35 accelerating device 3 the relay switch 4 is energized to short circuit the starting resistance and upon response establishes a maintaining circuit for itself independent of the accelerating device. The accelerating 40 device is then deenergizable by depression of the switch 27 to return the switch arm 14 to circuit closing position to thereby short circuit the field resistance R² for deceleration 45 of the motor. After such deceleration the switch 27 may be locked in its dotted line position for continued operation at reduced speed or may be returned to the position illustrated for re-acceleration of the motor.

Referring now to the circuit connections, 50 current is supplied from lines L and L' and the motor circuit may be traced as follows: With the main switch 2 closed, and the accelerating device inert, circuit extends from line L by conductor 30 through the regulating resistance R', by conductor 31 through the motor armature, by conductor 32 through contacts 2^a of switch 2, by conductor 33 through the series field F to line L'. The shunt field circuit of the motor extends from 55 line L by conductor 30 to segment 23, and with the regulator arm in position illustrated, to segment 22, by conductor 34 through the shunt field winding f to conductor 33 and thence to line L' as already traced.

60 A parallel circuit for the shunt field winding

f also extends from line L by conductor 36 through the shaft of the accelerating device to switch arm 14 and its coöperating contacts, by conductor 37 to conductor 34 and through said field shunt winding. Thus it 70 will be apparent that even with the regulator arm set in position (as shown in dotted lines) to include the field resistance, or a portion thereof, the entire field resistance would nevertheless be short circuited by the 75 accelerating device so long as the same retains said arm 14 in circuit closing position. When the accelerating device is operated then the motor circuit temporarily extends from line L by conductor 36 through the device 3 and its resistance R by conductor 38 to the regulator arm whereby the inclusion of the regulating resistance R' is dependent upon the position of said arm. When the resistance R is excluded from circuit and relay 80 85 4 is energized then said relay connects the regulator arm directly to line L by conductors 38, 39 and 40 thereby paralleling the accelerating device 3. Also if desired the relay might be employed to short circuit the 90 regulating resistance as by connecting the same to conductor 31 instead of to the regulator arm.

Assume now that it is desired to inch the motor. This merely requires setting of the 95 switch 25 in its dotted line position and depression of switch 27 to engage and bridge contacts 29. Circuit is thereby completed from line L by conductors 40 and 41 through the winding of main switch 2, by conductor 42 through contacts 29 of push button switch 27, by conductor 43 to line L'. Switch 2 thereupon responds to close the motor circuit as above described through all of the armature regulating resistance R' irrespective of 100 the setting of the regulator arm. Switch 2, however, is maintained energized only during depression of the switch 27 and immediately upon release of the latter the former is deenergized to disconnect the motor from 105 circuit.

Assume now that it is desired to start the motor and bring the same up to the speed provided for by setting of the regulator arm in the dotted line position. This 110 merely requires setting of the push button switch 25 in its full line position, the depression of the switch 27 to bridge contacts 29 and the release of said latter switch to reengage and bridge its contacts 28. Depression of switch 27 completes the energizing circuit of switch 2 as already traced and switch 2 in closing completes for itself a maintaining circuit which may be traced 115 from the right hand contact 29 of switch 27, by conductor 45 through push button switch 25, through a protective resistance 46, by conductor 47 through contacts 2^c of switch 2, to conductor 33 and thence through the series field winding to line L'. Switch 120

2 is thereby rendered independent of push button switch 27 for continued energization thereof and the return of said push button switch to engagement with contacts 28 completes the energizing circuit of the accelerating device. This circuit extends from line L by conductors 36 and 48 through the sole-
 5 noid winding of said device, by conductor 49 through contacts 28 of switch 27, by conductor 50 to conductor 47 and thence to line L', as already traced. The accelerating device is thereupon operated to establish a circuit for the motor armature through the resistance R, as above set forth, and to
 10 immediately remove said resistance R in a step-by-step manner. Following removal of the resistance R the arm 14 is moved to circuit opening position, thereby removing the short circuit from the field resistance
 15 R² so that the portion of said resistance to the left of the regulator arm when in dotted line position is included in circuit with the shunt field winding. Finally the accelerating device, by movement of the arm
 20 13 to circuit closing position, establishes an energizing circuit for the relay switch 4. This circuit may be traced from line L by conductor 36 through the shaft of device 3 to arm 13 and its coöperating contacts, by
 25 conductor 51 through the winding of switch 4, by conductor 52 to conductor 47 and thence to line L', as already traced. Relay 4 upon response completes circuit between the regulator arm and line L as above de-
 30 scribed, and in addition establishes for itself a maintaining circuit through auxiliary contacts 4^a. The motor will then continue to operate at the speed predetermined by the position of the regulator arm, it, of
 35 course, being understood that the speed may be varied at will by manual adjustment of said arm.

Assume now that the motor is in operation with a weakened field and it is desired to decelerate the same from the control station. This may be accomplished by depression of the push button switch 27 to break circuit between contacts 28. The circuit of the solenoid 15 is thereby interrupted and
 45 this releases the device 3 which restores the arm 14 to circuit closing position. This in turn short circuits all of the field resistance which may happen to be included in the shunt field circuit and thereby slows down
 50 the motor. If it is desired to continue the operation of the motor at its reduced speed then the switch 27 is locked in dotted line position. On the other hand, if it is desired to restore the motor to its previously
 55 established speed then the push button switch 27 is released for reengagement with the contacts 28 which recloses the circuit of solenoid 14 with the results above described.

When the motor is in operation it may
 60 be stopped at will by depression of the
 65

push button switch 25 to deenergize the main switch 2. Main switch 2 in opening interrupts the circuit of the operating solenoid of the accelerating rheostat and the energizing circuit of relay 4 whereby the parts 70 are restored to proper position for re-starting.

Referring now to Fig. 2, the same shows a motor 60, a main switch 61, an accelerating device 62, a regulating device 63, and 75 a push button control station 64, all of which elements are identical with the corresponding elements of Fig. 1. Also, these elements function together in practically the same manner as in the controller of 80 Fig. 1, but in this instance the control station functions to decelerate the motor through the control of a relay 65 instead of through the control of the accelerating device. 85

The relay 65 has two sets of contacts 65^a and 65^b, the former controlling the energizing circuit of the accelerating device and the latter completing a short circuit around the field resistance when said relay switch 90 is deenergized. The energizing circuit of the relay is controlled by the push button switch 27 in a manner similar to that in which the operating solenoid of the accelerating device is controlled in Fig. 1. That 95 is to say, after the switch 27 is depressed to energize the main switch 61 its reengagement with its up contacts completes the energizing circuit of relay 65. Relay 65 then responds to energize the operating 100 solenoid of the accelerating device which upon full operation completes for itself a maintaining circuit through its contact arm 13 in parallel with the relay switch 65. The relay switch may then be deenergized by 105 depression of push button switch 27 without effecting the accelerating device and when deenergized short circuits the field resistance through its contacts 65^b. Obviously, therefore, the relay will function under the direction of the control station precisely as the device 3 of Fig. 1 to decelerate and re-accelerate the controlled motor. 110

The power connections of Fig. 2 are precisely the same as those of Fig. 1 except for 115 the elimination of the connections controlled by the relay 4 and the addition of a connection from line L by conductor 70 through contacts 65^b of relay switch 65, by conductor 71 to the left hand side of the field resistance R², said added connections providing the field resistance with the short circuit above discussed. 120

The control circuits are also the same as those shown in Fig. 1 except for the circuits 125 of the operating solenoid of the accelerating device and the winding of relay switch 65. The circuit of relay switch 65 extends from line L by conductors 70 and 73 through said winding, by conductor 74 through the 130

up contacts of push button switch 27, and thence through the auxiliary contacts of main switch 61 to line L'. From these connections it will be apparent that the relay 5 65 is controllable by the switch 27, as above described. The energizing circuit for the operating solenoid of the accelerating device extends from line L by conductors 70 and 73 through the contacts 65^a of relay switch 65, 10 by conductors 75 and 76 through said solenoid, by conductor 77 to the return line for the winding of relay 65. Hence it will be apparent that the relay switch controls the energization of the accelerating device as 15 above described. The aforesaid maintaining circuit for the solenoid of device 62 may be traced from line L through the accelerating device to its arm 18 and its coöperating contact and thence by conductors 78 and 76 20 through said solenoid, as already traced. As will be apparent, this circuit is in parallel with contacts 65^a whereby said relay may be deenergized without effecting the accelerating device, as above set forth.

25 From the two embodiments of the invention illustrated, the numerous advantages thereof will be at once apparent. For example, provision is made for an exceedingly flexible control with a minimum number 30 of control switches and with a minimum number of electro-responsive control devices. Again, provision is made for speed control from either the push button station or the regulator in a manner to avoid all complications and interference.

What I claim as new and desire to secure by Letters Patent is:—

1. In a motor controller, in combination, electro-responsive starting and accelerating 40 means for the motor and a push button control switch therefor operable to effect starting and acceleration of the motor and also subsequently operable to effect deceleration of the motor but only to a predetermined accelerated speed.

2. In a motor controller, in combination, electro-responsive means to start and accelerate the motor and a push button control switch therefor operable to start the motor 50 and thereafter operable to accelerate and decelerate the same at will but subject to a predetermined decelerating limit established by said means upon response thereof.

3. In a motor controller, in combination, 55 electro-responsive means to start and accelerate the motor and a push button control switch for said means operable to effect starting and acceleration of the motor and subsequently operable to effect deceleration 60 of the motor, said means after response being partially independent of said switch to maintain at least a predetermined accelerated speed of the motor irrespective of subsequent operation of said switch.

65 4. In a motor controller, in combination,

electro-responsive means for starting and accelerating the motor, and a push button control switch therefor operable to effect starting and acceleration of the motor to a pre-established speed and thereafter operable to effect deceleration of the motor at will, said means upon accelerating the motor establishing a pre-arranged limit for the deceleration by said control switch.

5. In combination, a motor, electro-responsive means for completing the motor circuit and accelerating the motor by progressively regulating the armature and field circuits thereof, and a push button control switch for said means operable to effect starting and acceleration of the motor by both armature and field regulation, said switch being thereafter operable to effect deceleration but only by field regulation of the motor.

6. In combination, a motor, electro-responsive means for completing the motor circuit and accelerating the motor by progressively regulating the armature and field circuits thereof and a push button control switch for said means operable to effect starting and acceleration of the motor by both armature and field regulation, said switch being thereafter operable to effect deceleration and said means upon acceleration of the motor 95 functioning to limit the degree of deceleration by said switch to that obtainable through field regulation.

7. In combination, a motor, armature and field resistances for the motor, electro-responsive means for completing the motor circuit, for excluding said armature resistance and including said field resistance for acceleration of the motor, and a push button switch controlling said means to effect starting, acceleration and deceleration of the motor, said means acting upon response thereof to maintain the continuity of the motor circuit and exclusion of said armature resistance irrespective of decelerating operation of said switch.

8. In a motor controller, in combination, electro-responsive means for starting and accelerating the motor, a push button switch controlling said means, said switch being depressible to effect starting of the motor, returnable to initial position to effect acceleration of the motor and subsequently depressible to effect deceleration of the motor and connections to maintain a predetermined accelerated speed of the motor upon decelerating operation of said switch.

9. In a motor controller, in combination, electro-responsive means for starting and accelerating the motor, a push button control switch for said means depressible to effect starting of the motor, returnable to initial position to effect acceleration of the motor and subsequently depressible to decelerate the motor, said switch having

means to lock the same in depressed position and connections rendering said accelerating means partially independent of said switch upon decelerating operation of the latter.

10. In a motor controller, in combination, electro-responsive starting and accelerating means for the motor, and a control switch therefor to effect starting, acceleration and deceleration of the motor, said means including a relay determining the degree of deceleration obtainable by said switch.

11. In a controller for electric motors, in combination, electro-responsive starting and accelerating means and a control switch therefor to effect starting, acceleration and deceleration of the motor, said means including a relay functioning to render said means partially independent of said switch after acceleration of the motor.

12. In combination, a motor, armature and field resistances, electro-responsive means for progressively completing the motor circuit, excluding said armature resistance and including said field resistance, and a switch controlling said means to effect starting, acceleration and deceleration of the motor, said means including a relay to determine the degree of deceleration obtainable by said switch.

13. In combination, a motor, armature and field resistances, electro-responsive means for progressively completing the motor circuit, excluding said armature resistance and including said field resistance and a switch controlling said means to effect starting, acceleration and deceleration of

the motor, said means including short circuiting means for said armature resistance to remain unaffected by decelerating operation of said switch.

14. In combination, a motor, armature and field resistances, electro-responsive means for progressively completing the motor circuit, excluding said armature resistance and including said field resistance and controlling means for said former means to effect starting, acceleration and deceleration of the motor, said former means including a relay controlling an alternative short circuit around one of said resistances whereby said governing means is effective to exclude said field resistance for deceleration but ineffective to reinclude said armature resistance.

15. In combination, a motor, electro-responsive means controlling the continuity of the motor circuit, armature and field resistances for the motor, a common electro-responsive control device for said resistances and means controlling the aforesaid means to start, accelerate and decelerate the motor and a relay associated with said control device to govern alternative control circuits for one of said resistances whereby the decelerating action of said control means is limited to regulation of said field resistance.

In witness whereof, I have hereunto subscribed my name in the presence of two witnesses.

ALBERT J. HORTON.
